Primary Examiner—Caron Veynar*Assistant Examiner*—Ricky Pham(74) *Attorney, Agent, or Firm*—Collen IP; Donald J. Ranft**CLAIM**

The ornamental design for a watch case, as shown and described.

DESCRIPTION

FIG. 1 is a perspective view of my new, original and ornamental design for a watch case;

FIG. 2 is a perspective view in an opened state thereof; and,

FIG. 3 is a rear view thereof.

The broken lines shown in FIGS. 1 and 2 are for illustrative purposes only and form no part of the claimed design.
